UNITED STATES PATENT OFFICE

Patent No. 2,521,617, issued Sept. 5, 1950.

MEETING RAIL ENGAGING MEMBER FOR STORM WINDOWS

Clifford Lee Webster, Youngstown, Ohio, assignor to Aluminum Air Seal Manufacturing Company, Youngstown, Ohio, a corporation of Ohio

Application July 15, 1948, Serial No. 33,777

2 Claims. (Cl. 189—76)

1

This invention relates to storm windows in general and in particular to means for locking the meeting rails of a double hung storm window assembly to one another.

The principal object of the invention is the provision of a device for holding the meeting rails of a double hung storm window assembly in engagement with one another.

A further object of the invention is the provision of a device engageable in one of the meeting rails of the double hung storm window assembly for joining the meeting rails of the said window assembly when in closed position.

A still further object of the invention is the provision of an extruded metal part engageable in a metallic sash for self retention therein and having means thereon for engaging an adjacent metallic sash and urging the same toward the first mentioned sash.

The meeting rail engaging member for storm windows shown and described herein comprises a simple and efficient means for securing metallic framed storm window sash to one another and particularly the meeting rails thereof which have heretofore presented a problem in storm window construction.

As is known in the art, relatively lightweight metal extrusions are commonly employed as glass frames to form storm window sash and such storm window sash are commonly positioned in a mounting frame in double hung relation for vertical sliding motion therein. The sides and top and bottom portions of the sash which engage the frame are thus secured in an air-tight manner.

The meeting rails of the sash are normally positioned adjacent one another and heretofore have not been secured to one another with the result that wind pressure or deflection of the sash themselves separated the meeting rails and destroyed the effectiveness of the storm window assembly. The present invention eliminates this difficulty as it causes the meeting rails to move into close engagement with one another and provides tension therebetween thus enabling each of the meeting rails to support the other and at the same time maintain themselves in desirable face to face engagement.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed

2 without departing from the spirit of the invention.

The invention is illustrated in the accompanying drawing, wherein:

5 Figure 1 is a vertical section of a portion of the meeting rails of a pair of double hung storm window sash.

10 Figure 2 is a vertical section of a portion of the meeting rails of a pair of double hung storm window sash in open position.

15 Figure 3 is a plan view of a portion of the meeting rails of a pair of double hung storm window sash.

20 Figure 4 is a perspective elevation of the meeting rail engaging member.

25 By referring to the drawings and Figures 1 and 2 in particular it will be seen that portions of a pair of double hung storm window sash have been disclosed the transparent pane of the upper outer sash being indicated by the numeral 10

30 and its meeting rail metallic frame on its lower edge being indicated by the numeral 11. The transparent pane of the inner lower sash is indicated by the numeral 12 and the metallic meeting rail thereof is indicated by the numeral 13.

35 The transparent panes 10 and 12 are secured at the meeting rails 11 and 13 by metallic splines 14 and 15, respectively, as is customary in storm window practice. In Figure 1 of the drawings

40 the meeting rails 11 and 13, respectively, are shown in face to face engagement which is their normal position when the storm window is closed.

45 In Figure 2 of the drawings the meeting rails 11 and 13 are shown in disengaged relation as is the case when the lower inner pane 12 is elevated or

50 the upper outer pane 10 lowered.

Still referring to Figures 1 and 2 of the drawings it will be observed that the upper edge of the meeting rail 13, which is positioned on the upper edge of the pane 12 of the lower inner sash, has a relatively short section of an engaging member 16 slidably engaged therein and preferably positioned in the center thereof with respect to the sides thereof (not shown). The

55 engaging member 16 comprises an extruded metal shape, the body portion of which registers within a channel 17 of the meeting rail 13 and partially beneath a flange 18 thereof. The body portion of the engaging member 16 is formed to

60 overlie the upper edges of the meeting rail 13 by reason of a pair of flanges 19 and 20, the flange 19 being relatively short and the flange 20 extending outwardly and having its outermost, lowermost edge slightly outturned as indicated by the numeral 21.

65 The engaging member 16 is shown in perspective

70 view in Figure 4.

tive in Figure 4 but it will be observed by referring thereto that its cross sectional shape is such that it will register with the channel 17 of the meeting rail 13 and thereby enable the same to be slid into position longitudinally thereof at the time of formation of the storm sash, and to be self retaining therein. In position, as shown in Figures 1, 2 and 3 of the drawings, the engaging member 16 lies midway between the sides of the sash so that the depending flange 20 will slidably engage and tension a spline receiving channel 22 formed in the upper edge of the meeting rail 11 which is on the lower edge of the transparent pane 10. The action of the engaging member is illustrated in Figures 1 and 2 of the drawings.

In Figure 2 of the drawings the sash are shown in disengaged or partly open position with the meeting rails out of engagement. In Figure 1 of the drawings the sash are shown in engaged or fully closed position, it being observed that the meeting rails 11 and 13 are in face to face engagement and held in that engagement by the tensioning action of the engaging member 16 and specifically the depending flange 20 thereof which engages the meeting rail 11.

It will thus be seen that a simple and efficient device has been disclosed which may be inexpensively formed and easily applied to storm window constructions and particularly those employing metallic frames such as shown herein. It will also be seen that in operation the engaging member will efficiently hold the meeting rails of the storm window sash in tight face to face engagement whereby they become self-supporting and whereby any possibility of air leakage at this point of the storm window construction is eliminated.

Having thus described my invention, what I claim is:

1. A double hung storm window comprising upper and lower vertically slidable sashes each including a metal frame, the meeting rails of the sash frames each comprising an upwardly facing channeled part, and the channeled parts of the meeting rails having straight inner side wall portions to fit one against the other when the sashes are in closed position, and a member for holding the meeting rails of the sashes in engagement with each other when the same are in closed position, said member comprising a main longitudinally extending body part fitting into the channeled part of the meeting rail of the lower sash with opposite side faces thereof in close fitting engagement with the straight side wall portions of said channeled part, said mem-

ber and the channeled part interfitting with each other to form an interlocking connection between said member and said channeled part, the body part of said member having a laterally extending portion overlying the upper edge of the straight inner side wall portion of the last mentioned channeled part, and a flange extending downwardly from said laterally extending portion to fit against the inner side of the straight inner side wall portion of the channeled part of the meeting rail of the upper sash.

2. A double hung storm window assembly comprising upper and lower vertically slidable sashes each including a metal frame, the meeting rails of the frames of the sashes each comprising an upwardly facing channeled part, and the channeled parts of the meeting rails having straight inner side wall portions to fit one against the other when the sashes are in closed position, the straight inner side wall portion of the channeled part of the meeting rail of the lower sash having at its upper edge a flange extending laterally to the inner side thereof, and a member for holding the meeting rails of the sashes in engagement with each other when the same are in closed position, said member comprising a main longitudinally extending body part having at one side at its upper part a longitudinally extending shouldered portion, said body part fitting into the channeled part of the meeting rail of the lower sash with its shouldered portion in interlocking engagement with the laterally extending flange on said side wall portion, and said body part having a laterally extending portion overlying the upper edge of said straight side wall portion, and a flange extending downwardly from said laterally extending portion to fit against the inner side of the straight inner side wall portion of the channeled part of the meeting rail of the upper sash.
